UNITED STATES PATENT OFFICE.

HUGH SHERRILL, OF MAGNOLIA, ARKANSAS.

HAWK CALLER.

Application filed July 22, 1924. Serial No. 727,493.

To all whom it may concern:

Be it known that I, HUGH SHERRILL, a citizen of the United States, residing at Magnolia, in the county of Columbia and State of Arkansas, have invented certain new and useful Improvements in a Hawk Caller, of which the following is a specification.

My invention relates to wind instruments and in particular to instruments adapted to be used by hunters. The primary object of the invention is to provide an instrument, which when blown upon, will produce a sound simulating the cry of a hawk, which is effective for hawk calling.

Another object of the invention is the provision of an instrument of this character constructed of relatively few parts and which is extremely efficient and durable.

With these objects in view and such others as will be apparent from the description, the invention resides in the novel construction combination and arrangement of parts hereinafter described and claimed, and illustrated in the accompanying drawings of which:—

Figure 1, is an elevation of an instrument constructed in accordance with the principles of the invention,

Figure 2, a vertical section therethrough, and

Figure 3, a fragmentary vertical section through the reed portion of the instrument.

In detail the invention comprises a wooden tube 1 rounded at one end so as to provide a mouthpiece and having adjacent at opposite end a finger grip bulge 3 on its periphery.

Disposed over the end of the tube adjacent the finger grip bulge is a ribbed ferrule 4 on which cord may be wound for attaching the instrument to the belt of a person using same. Seated within the bore of the tube over the end adjacent to the ferrule is a bushing 5 suitably secured therein and extending for a short distance into the bore.

The bushing 5 is formed to receive therein a relatively short metal cylinder 6 provided with a flat outer end 7. The inner end of the cylinder 6 terminates at the end of the bushing 5, and the cylinder is retained within the bushing in frictional engagement therewith.

Disposed within the bore of the cylinder 6 is a semicylindrical block 8 provided on its flat face with a groove 9 extending longi-

tudinally of the block from one end and sloping gradually to terminate at a short distance from the opposite end of the block. On either side of the groove 9 the flat face of the block is cut away to provide shoulders 10 adjacent to one end of the block and a reed tongue of thin vibratory metal as at 11 is disposed over the groove 9 completely to cover a portion thereof, and resting against the inner ends of the shoulders 10. The reed 11 is clamped in position on the block by means of a semicylindrical cork 12 placed there to act in conjunction with the block 8 completely to fill the interior of the bore of the cylinder 6. The innermost end of the reed 11 towards the mouthpiece 2, is bent to extend away from the block 8 so as to provide for the necessary air passage therein and into the groove 9.

In assembled position the various elements described are disposed as illustrated best in Figure 2 with the wooden block 8 extended from within the cylinder 6 approximately the same distance within the bore of tube 1, and the inner end of the cylinder is closed by the cork 12 which further serves to clamp the reed member 11 in position over the groove 9. In this construction when the instrument is blown upon from the mouthpiece end 2 the only passage for air therethrough will be under the reed 11 and through the groove 9. The arrangement of the reed is such that the sound produced by the rapid vibration thereof, will be similar to the cry of a hawk.

This instrument has been found very effective to call in hawks and like birds of prey where it is desired to exterminate the same. An attached cord may be applied over the ferrule 4, so that the instrument may be readily attached to the belt or garment of the person using the same. The bulge 3 supplies an efficient hand grip, and the tube 1 is preferably formed of soft wood which may be finished to provide a neat and attractive appearance.

While I have illustrated and described certain details and materials entering into the construction and operation of the invention, I desire it to be understood that the invention is not limited thereby, but that any desired changes and modifications may be made in the structural details as will fall within the scope of the invention as claimed.

I claim:—

An instrument of the character described

comprising a hollow tube forming a mouth-piece, a hollow cylinder fitted in the outer end of said tube and projecting beyond the end thereof, an outwardly flared outer end 5 on said cylinder, a block semi-cylindrical throughout its length disposed in the inner end of the cylinder and having a longitudinally extending groove in the flat face extending from a point adjacent the inner 10 end to the outer end thereof, a vibratory

reed over said groove extending from a point adjacent the outer end and outwardly bent at its inner end, the inner end of said reed being tongue shaped, and a closure member for the inner end of the cylinder 15 disposed over said reed member and block for clamping the reed member in position.

In testimony whereof I affix my signature.

HUGH SHERRILL.
